UNITED STATES PATENT OFFICE.

LESTER C. BEARDSLEY, OF CLEVELAND, OHIO.

DESIGN FOR A CAMPAIGN-TORCH.

SPECIFICATION forming part of Design No. 18,611, dated September 18, 1888.

Application filed August 2, 1888. Serial No. 281,824. Term of patent 3½ years.

To all whom it may concern:

Be it known that I, LESTER C. BEARDSLEY, a citizen of the United States, residing at Cleveland, in the county of Cuyahoga and State 5 of Ohio, have invented a new and original Design for a Campaign-Torch, of which the following is a specification.

The nature of my design is fully shown in the accompanying drawing.

10 The design consists in a torch the body of which has the form and configuration of a C-shaped body provided with a central vertical

projection at the top, as shown. The body is in the form of a block-letter C in its general contour.

15

I claim—

The design for a campaign-torch herein shown and described, consisting of the C-shaped body provided with a central vertical projection at the top, as shown.

LESTER C. BEARDSLEY.
